US00D945192S

(12) **United States Design Patent** (10) Patent No.: **US D945,192 S**
(45) Date of Patent: **** Mar. 8, 2022**

(54) **PRODUCT DISPLAY UNIT**(71) Applicant: **Apple Inc.**, Cupertino, CA (US)(72) Inventors: **Jean-Marc Gady**, Los Altos, CA (US); **Seung Chae Kang**, New York, NY (US); **Gabriel J. Lamb**, Burlingame, CA (US); **Adrian E. Magrina**, San Francisco, CA (US); **Indhu V. Solayappan**, Sunnyvale, CA (US); **Moritz Wilsberg**, Rheinbreitbach (DE)(73) Assignee: **Apple Inc.**, Cupertino, CA (US)(**) Term: **15 Years**(21) Appl. No.: **29/809,010**(22) Filed: **Sep. 24, 2021****Related U.S. Application Data**

(63) Continuation of application No. 29/753,854, filed on Oct. 2, 2020, now Pat. No. Des. 931,665, which is a continuation of application No. 29/744,096, filed on Jul. 27, 2020, now Pat. No. Des. 897,746, which is a continuation of application No. 29/693,874, filed on Jun. 5, 2019, now Pat. No. Des. 891,158.

Primary Examiner — Kelley A Donnelly*(74) Attorney, Agent, or Firm* — Sterne, Kessler, Goldstein & Fox P.L.L.C.**CLAIM**

The ornamental design for a product display unit, as shown and described.

DESCRIPTION

FIG. 1 is a top front perspective view of a product display unit showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the product display unit that form no part of the claimed design.
